UNITED STATES PATENT OFFICE.

EDWARD M. ADAMS, OF LENNOXVILLE, QUEBEC, CANADA.

PULLEY.

Application filed September 4, 1925. Serial No. 54,459.

This invention relates generally to improvements in rope pulleys and more particularly to light duty pulleys, such as are used for clothes lines and the like, and the 5 object of the invention is to provide an inexpensive, durable and efficient pulley.

A further object is to provide a pulley having the frame so constructed that a rope travelling in the sheave is positively held 10 against escape from the groove of the sheave and also from binding between the sheave and frame.

A still further object is to provide a pulley of this type in which the frame is composed of wire in sections easily manufactured and assembled.

Various other objects and the advantages of the invention may be ascertained from the following description.

20 A pulley formed according to this invention comprises essentially a grooved sheave pivotally mounted in a frame composed of two similar sections connected to one another and to a strap member by which the 25 pulley is suspended.

In the accompanying drawings which illustrate one embodiment of the invention and one of many possible modifications;

Fig. 1 is a side elevation of the pulley.

30 Fig. 2 is a plan view thereof.

Fig. 3 is an edge elevation.

Fig. 4 is a perspective view of one of the frame members.

Fig. 5 is an elevation of the strap member.

35 Fig. 6 is a fragmentary plan view showing a slight modification.

Referring more particularly to the drawings, 11 designates a grooved sheave of wood or other suitable material, mounted in a 40 frame composed of a pair of similar members 12 and a strap 13. The sheave is rotatably mounted in the frame by means of a spindle 14 and is held from rubbing on the frame and strap by washers or a hub, designated 15.

Each of the frame members 12 is formed of a piece of heavy wire or light rod bent to the form shown in Figure 4. The wire forming the frame member is in the embodiment illustrated bent as follows:—At one end a loop or eye 16 is provided. The wire is then bent in substantially semicircular form, as at 17, the radius of the bend being somewhat larger than the radius of the sheave. In the middle of the semicircularly 55 bent portion, the wire is bent to form a loop

18 and, at the opposite end of the semicircular portion from the loop 16, the wire is bent to form a loop 19. The loops 16, 18 and 19 are formed inside the curve of the 60 semicircular portion, as clearly shown, and each loop is of substantially the same internal diameter as the external diameter of the wire itself. From the loop 19 the wire extends in a substantially straight portion 65 20 to the loop 16 and is bent approximately at right angles at 21, so as to pass through the loop 16. Midway of its ends, the straight portion 20 is formed into a depending loop 22 of a size to tightly hold the spindle 14. 70 Beyond the loop 16 the wire is bent at approximately right angles, as at 21^a, in the opposite direction to the bend 21, the two bends being so closely spaced that the loop 16 is held tightly between them. Beyond 75 the bend 21^a, the wire is bent in substantially semicircular form, as at 23, the portion 23 lying in a plane at right angles to the plane of the portion 17. Beyond the semicircular portion 23, the wire is bent at approximately 80 right angles, as at 24, and then continues for a short distance in a straight line to its extremity, thus forming a straight portion 25 approximately at right angles to the straight portion 20 and in axial alignment with the 85 eye 16.

The strap member 13 comprises a piece of wire bent to approximately U-shape at its centre to form a large loop 26, by means of which the pulley may be suspended from a hook or the like. Beyond the loop or U-shaped portion 26, the two arms 27 of the wire are offset outwardly, as at 28, so as to space the two arms sufficiently apart to receive the pulley sheave between them. These 90 arms then extend in an approximately straight line to nearly their extremities, where they are bent sharply toward one another, as at 29. The distance between the offsets 28 and the inturned ends 29 is slightly 95 greater than the diameter of the pulley sheave. Midway between the offsets 28 and the inturned ends 29 the strap arms 27 are bent into loops 30 of a size to receive the spindle 14. 100

105 The elements of the frame and the sheave may be assembled together in a variety of ways as may be found most convenient. One such method of assembly is to connect two frame members 12 together by passing the 110 extremity 25 of each member through the loop 19 of the other member and then bend-

ing the portion 25 of each member upon the portion 20 of the other member, as illustrated at 31, Figures 1 and 2. This method of assembly forms a frame adapted to encircle the pulley sheave slightly above what may be termed its horizontal diameter, as will be seen in Figures 1 and 2. When the frame is properly proportioned to the sheave, the loops 16 and 19 lie inside the planes of the sheave flanks and so close against the outer edge of the sheave flanges as to prevent a rope climbing out of the sheave groove from entering between the sheave and the frame members 20. The portions 23 of the frame form keepers to retain a rope on the sheave. The strap member 13 is now passed between the portions 20 of the frame and its lower inturned ends 29 passed inwardly through the loops 18 of the frame and bent over as at 32, Figures 3 and 4, to make the connection permanent. The strap may now be swung to one end of the frame to permit insertion of the pulley sheave and then moved into a position at right angles to the frame portions 20, as clearly shown in Figure 1. When thus moved, the loops 30 of the strap member will register with the loops 22 of the frame members and the spindle 14 may be passed through all four loops and through the sheave, washers as indicated at 15 being inserted as desired, or if the pulley has no hub projecting beyond its flanks. The spindle is preferably a tight driving fit in the loops 22 and 30 so as to make the frame rigid. The ends of the spindle may now be slightly burred over to hold the same against escape. When thus assembled, the offsets 28 of the strap member lie close to the sheave flanges and prevent a rope which may climb either flange from entering between the sheave and the strap member.

In the embodiment illustrated, the loops 22 are formed within the semicircle of the frame, in which case the frame portions 20 occupy positions above the diameter of the sheave but, it will be understood that this is not essential, and that the loops 22 may be turned outwardly. It will also be seen that both loops 30 of the strap member are formed on one side thereof, so that the strap member occupies a plane slightly to one side of the vertical diameter of the sheave. This disposition of the loops is purely a matter of convenience in bending the wire and it will be understood that the loops may be turned in opposite directions if desired. The loops 16, 18 and 19 are formed within the semicircle of the frame, principally to impart a smooth outer edge to the frame, and it will be understood that this inward turning of the loops is not essential but may be departed from and the semicircular portions 17 thereby brought closer to the periphery of the sheave.

In Figure 6, there is illustrated a slight modification of the frame members in which the part 23^a corresponding to the part 23 of Figure 2 is turned inwardly instead of outwardly, as in Figure 2, for the purpose of confining a rope more closely to the groove of the sheave. Such a formation of the frame will not permit the passage of a knot or other enlargement on the rope, such as would pass through a frame formed according to Figure 2.

From the foregoing description, it will be understood that the invention is not confined to the details of the embodiment illustrated but is capable of modification in a variety of ways as may be convenient or expedient in manufacture and use, and that all such modified forms as fall within the scope of the appended claims are deemed to be included in and to form a part of the invention.

Having thus described my invention, what I claim is:—

1. In a device of the class described, a sheave and a frame enclosing the sheave comprising a pair of members, each formed of a single piece of wire bent to semicircular shape and provided at the ends and centre of the curved edge thereof with loops, said wire being passed adjacent one of its ends through a loop formed at the other end and leaving a projecting portion adapted for insertion through a loop of the other member, a strap member connected at its ends to said similar members, all three of said frame members being provided with loops for the passage of a spindle to support the sheave.

2. In a device of the class described, a sheave and a frame comprising three members, two of which are similar and formed of wire, each including a semicircular portion, loops at the ends, and centre of such semicircular portion, a straight portion having a loop at its centre and extending from one of said end loops and passing through the other of said end loops and bent to form a shoulder, and a fastening portion beyond the shoulder passing through an end loop of the other of the two members, and a strap member secured at its ends in the centre loops of the semicircular portions and formed to provide apertures in register with the centre loops of the straight portions of the first named members for the passage of a spindle, and a spindle passing through the loops of the frame members and the aperture of the strap member and through the sheave and connecting the strap member and frame members and rotatably supporting the sheave.

3. In a device of the class described, a grooved sheave and a frame enclosing the sheave formed of wire, said frame projecting inwardly of the planes of the sheave sides at points slightly beyond the periphery

of the sheave to hold a rope in the sheave groove against climbing out of the groove and entering between the flanks of the sheave and the frame.

5 4. In a device of the class described, a grooved sheave and a frame enclosing the sheave comprising a pair of semicircular members of slightly greater diameter than the sheave and located in planes slightly in
10 side the planes of the sheave flanks whereby said members constitute a guard beyond the periphery of the flanges forming the sheave groove, a pair of substantially diametrically arranged members each connecting the ends
15 of one of the semicircular members, said diametrical members being located outside the planes of the sheave flanks and each provided with an aperture midway of its ends, each of said semicircular members being
20 formed integral with one of the diametrical

members and constituting a frame member, connecting means extending between the frame members at the ends of the diametrical members and each formed integral with one of the members and inserted through an 25 aperture of the other member, each of said frame members with the attached connecting member being formed of a single piece of wire, and a strap member presenting apertures in alignment with the central 30 aperture of the diametrical frame member portions, said strap member being bent at its ends around the semicircular frame member portions, and a spindle passing through the strap member and frame member apertures and connecting the same together and supporting the sheave.

In witness whereof, I have hereunto set my hand.

EDWARD M. ADAMS.
